Specification for Design.

Patented July 13, 1920.

Application filed October 24, 1919. Serial No. 333,132. Term of patent 3½ years.

To all whom it may concern:

Be it known that I, EDUARDO MALAVARCA, a subject of the King of Italy, and a resident of Newark, in the county of Essex and State of New Jersey, have invented a new, original, and ornamental Design for a Doll, of which the following is a specification, reference being had to the accompanying drawing, forming part hereof.

The drawing illustrates a face view of the doll showing my new design.

I claim:

The ornamental design for a doll as shown.

EDUARDO MALAVARCA.
